(57) CLAIM

The ornamental design for a container for hair care composition, as shown and described.

DESCRIPTION

FIG. 1 is a top, front, and right side perspective view showing a first embodiment of our new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a top, front, and right side perspective view showing a second embodiment of our new design;

FIG. 9 is a front elevational view thereof;

FIG. 10 is a back elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines shown on the bottom surface in the FIGS. 7 & 14 drawing views are included for the purpose of showing environmental structure that forms no part of the claimed design.
